UNITED STATES PATENT OFFICE.

FREDERICK E. CARLSON, OF NEW BRITAIN, CONNECTICUT, ASSIGNOR TO LANDERS, FEARY & CLARK, OF NEW BRITAIN, CONNECTICUT, A CORPORATION OF CONNECTICUT.

SPACER FOR VACUUM-RECEPTACLES.

1,186,545.

Specification of Letters Patent. Patented June 13, 1916.

Application filed July 29, 1915. Serial No. 42,648

To all whom it may concern:

Be it known that I, FREDERICK E. CARLSON, a citizen of the United States, and a resident of New Britain, in the county of Hartford, State of Connecticut, have invented certain new and useful Improvements in Spacers for Vacuum-Receptacles, of which the following is a specification.

The object of this invention is to provide a new and improved means by which a vacuum receptacle made of fragile material, such as glass, can be so supported within the metallic case as to minimize breakage due to sudden jars or jolts.

15 In the drawings—Figure 1 is a central vertical section of a complete receptacle and case, equipped with the spacer constituting this invention. Fig. 2 is a transverse section view on enlarged scale.

20 Referring to the drawings, *a* denotes the case, which is usually of metal, *b* the cap connected to the case as by screw threads, *c* a cushioning gasket to bear upon the neck of the receptacle, and *d* the receptacle, which 25 as shown is of double-walled construction, the space between the walls being evacuated.

e denotes the spacers, which consist of a plurality of, and preferably four, separate strips of resilient material, preferably metal, 30 arranged longitudinally between the receptacle and the case, bearing at their edges on the case and contacting with the receptacle along their median line for a substantial, if not the greater, portion of the length of the 35 receptacle. The width of these strips is such that when the receptacle is in place they are slightly bowed, as indicated in Fig. 2, insuring that at all times the receptacle is securely supported within the case. Any unusual jar or jolt which throws the receptacle to one side of the case is counteracted by the resiliency of the spacers which will 40 bow slightly, and since the receptacle has a bearing against the strips for the greater part of its length, the blow is distributed over a large area of the receptacle wall. I prefer to connect the strips in pairs underneath the bottom of the receptacle, as shown in Fig. 1, but my invention is not concerned 45 with this part of the structure.

Fig. 1 of the drawings illustrates spring fingers *g*, in which the bottom of the receptacle rests, although any desirable and suitable support of this character may be utilized.

55 The feature of the invention to which attention is particularly directed is the bearing of the spacers along their edges against the inner wall of the case, and the bearing of the receptacle against the central portion 60 of the spacers, and preferably the bearing of the spacers against the case, and of the receptacle against them, extends for a considerable distance as distinguished from anything in the nature of point contact.

65 I claim as my invention—

1. The combination with a case and a vacuum receptacle of fragile material located therein, of a plurality of resilient metallic spacers arranged longitudinally between said case and receptacle and spaced from one another, the edges of said spacers resting against the inner wall of said case, and said receptacle bearing against the central portion of said spacers throughout the greater part of their length.

70 2. The combination with a case and a vacuum receptacle of fragile material located therein, of a plurality of independently acting resilient metallic strips arranged longitudinally between said case and receptacle, said strips bearing along their edges against the interior of said case, said receptacle bearing against said strips at their central part throughout the greater part of 75 their length.

80 3. The combination with a case and a vacuum receptacle of fragile material located therein, of a plurality of strips of resilient material arranged longitudinally 85 between said case and receptacle and adapted for action independently of one another, said strips throughout the greater part of their length bearing at their edges against the inner wall of said case, and at their central portion against said receptacle.

85 FREDERICK E. CARLSON
